UNITED STATES PATENT OFFICE.

SIMON W. WARDWELL, OF PROVIDENCE, RHODE ISLAND.

BRAIDING-MACHINE CARRIER.

1,025,172.

Specification of Letters Patent.

Patented May 7, 1912.

Application filed May 3, 1909. Serial No. 493,719.

To all whom it may concern:

Be it known that I, SIMON W. WARDWELL, a citizen of the United States, residing at Providence, in the county of Providence and State of Rhode Island, have invented certain new and useful Improvements in Braiding-Machine Carriers, of which the following is a specification.

My invention is an improvement in carriers for braiding machines, and particularly for machines of that type in which the yarns from one bank or tier of yarn supplies pass the supplies of another tier with interlacing action to form a braid.

The purpose of my invention is to provide superlative sensitiveness of response to light tension variations with capacity to control heavy fluctuations, combining the two requirements in one structure that is staunch and durable.

The novel and meritorious features of my invention are fully disclosed in the following specification and accompanying drawings which show respectively: Figure 1 is 25 a side elevation of the carrier partly in section on line *a—a* of Fig. 2; Fig. 2, a plan view looking down in the direction of the arrow *A* in part section on line *d—d*; Fig. 3 is an enlarged view, sectional on the line *b—b* in Fig. 2; Fig. 4 is a section on the line *c—c* of Fig. 2; Fig. 5 is an enlarged sectional view on the line *a—a* of Fig. 2, showing the mode of securing the supply holder stem 9 to the base 8.

The body of the carrier is composed of a deck portion 2, and runner 3, preferably made in one piece as shown. On the body is mounted the yarn supply holder 4, which turns on the stud 5, the latter having a 40 shoulder 6 for an abutment or bearing to prevent end play of the supply holder, and projecting upward sufficiently to engage and retain the cap or guard 7 over which travel the yarns from the other bank of supplies.

The supply holder 4 is composed of a base 8 and a stem 9 which carries blades or spurs 10 to rotatively secure the cap or bobbin, whichever is employed as a container for the yarn. The base 8 is, in form, a shallow, cylindrical cup, having ratchet teeth 11 formed in the interior surface of its rim. Engaging the ratchet teeth is a detent or pawl 12 which may be of any suitable construction, but preferably is formed of wire to the appropriate shape, one extremity bent to form

the trunnion 13—Fig. 4, which enters a bearing 14 in the carrier body, and the other shaped to constitute the toe 15 or acting portion of the pawl; the pawl is so related to the supply holder base as to rely on the latter to hold it into its bearing 14, without special securing device. A spring 16, coiled about the trunnion 13 engages by one end the body of the pawl and by the other some fixed object in the carrier, such as one of the 60 abutments 17, thereby acting to engage the toe 15 of the pawl with the ratchet teeth of the carrier base.

The pawl is controlled by the yarn in the following manner. From the abutments 17, 70 there rises a standard 19, made preferably of sheet metal in the form of a narrow arch whose feet 20 are secured to said abutments by screws 21, 21. Within the abutments are formed bearings 22, for a rocker 23, which 75 is held in said bearings by the feet 20 of the standard 19. This rocker 23, has a crank 24, and at each extremity an arm, one 25, to engage the pawl 12, and the other 26 for purposes of tension adjustment, as will be 80 described later. Connected with the crank 24, is a finger or member 27—Fig. 1, which rises from the crank and within the arch of the standard 19, two guide pins 28—28 through the sides of the standard 19, maintain the member 27 in its upright position. The upper end of the member 27 is hooked, 85 to receive the yarn from the supply, which yarn passes through the thread ways or slots 30 in the standard 19. Under tension, 90 the draft of the yarn so passing through the standard will suffice to uphold the member 27, and when insufficient yarn is being delivered will draw it up so that the arm 25 will be caused to engage the pawl 12, moving it in the direction of the arrow *B*, Fig. 2, and releasing the supply holder so it can turn and deliver yarn. If the yarn delivers too freely, the slackening of tension on the 95 yarn will cause the member 27 to drop, permitting the pawl 12 to reengage the teeth of the supply holder base and restrain the supply holder from rotation.

The degree of tension on the yarn is secured by established suitable resistance of 105 the member 27 to suspension. To the arm 26 is connected a spring 31 which is appropriately anchored. The intensity of action of this spring can be varied by any suitable means, such as by the substitution of a 110

heavier spring for a lighter one or vice versa, but I prefer to effect such variations in the following manner. The spring 31 is anchored to an arm 32 which is preferably mounted on the hub 33 which constitutes the bottom bearing of the supply holder 4, and receives the stud 5. Concentric with the axis of the supply holder and preferably on the under side of the deck is a notched bearing or retainer 34 for the arm 32, and the notches of this bearing are graduated numerically to facilitate uniform adjustment on different carriers. The length of the notched bearing 34 is so related to the tension and extensibility of the spring as to provide adequate range of tension adjustment which can obviously be further modified by substituting different springs as before stated.

The mode of securing the cop holder stem 9 to the base 8 and particularly of securing the blades 10 is unique. A prerequisite of the cop holder structure is lightness, and the use of an extremely light tube for the cop holder stem is incompatible with rigid securing to the base by such usual process as riveting, heading over, etc. Further, the thin shell of a light tube is insufficient to properly hold the blades 10. There is therefore made a bushing 35 of substantial wall which extends into the stem 9 sufficiently to take the blades, and which is forced solidly into place. Cuts are then made through the shell of the stem 9, into the bushing 35 and the blades 10 are forced solidly into the bushing 35 through the shell of the stem 9. The stem 9 is then forced into the base 8, up to the shoulder 36 of said stem and the shell of the stem is then riveted over, the bushing supporting the shell and securing solid contact with the base—Fig. 5. The bushing 35 extends within the metal of the base so as to force the shell of the stem solidly against the same and aid to support the stress of riveting, preventing buckling and crimping of the shell.

In operation, the yarn *y* is drawn from the supply (indicated by broken lines) through the slots 30 of the standard 19 and under the hooked upper end of the member 27. As the braiding operation progresses, the yarn is taken up and raises the member 27, thereby causing action of the rocker 23, through its arm 25, on the pawl 12, to release the supply holder that it may deliver yarn. When the yarn is given off from the supply with such freedom as to cause the member 27 to drop, such action withdraws the arm 25 from the pawl 12, causing the latter to reengage the supply holder and restrain it from delivering yarn.

The simplicity, lightness and efficacy of the foregoing construction are of great moment in such machines as that to which this device applies, where the highest attain-

ments of speed and efficiency are secured only through the creation of structures specially devised to meet the unusual conditions imposed. Complicated mechanism and ponderous parts are here avoided, but strength and capacity for substantial endurance are not sacrificed. The parts are well protected, immune from destructive contact even with outside articles. The member 27, or yarn finger, is housed by the arched standard 19, the rocker 23 lies substantially flat on the surface of the carrier deck, in which is a clearance pocket 37 for the lower end of the yarn finger 27. An aperture 38 in the carrier deck permits the spring arm 26 of the rocker 23 to connect below the deck with the tension spring 31 and its adjusting arm 32. The pawl 12 projects above the deck between the cop holder base 8 and the standard 19, while an aperture 39 in the deck, permits it to extend below the same, under the edge of the rim 40 of the base 8 of the cop holder and upward, within said base to engage the internal teeth above referred to.

Without limiting myself to the precise form of construction described, I claim:

1. In a tension device for braider carriers, the combination with a cop holder having a cupped base and teeth in the interior surface of the rim of said base, of a spring actuated pawl to engage said teeth, a resiliently yielding yarn finger acted upon by the yarn delivered by the cop holder and means intermediate the yarn finger and pawl whereby the latter is caused to engage or disengage the cop holder, with varying tension of said yarn.

2. In a tension device for a braider carrier, the combination with a cop holder having a cupped base and teeth in the interior of the rim of said base, of a pawl to engage said teeth, a resiliently resisting yarn finger acted upon by the yarn delivered by the cop holder, means to vary the degree of said resistance and an intermediary between the yarn finger and pawl whereby the latter is caused to engage or disengage the cop holder, with varying tension of said yarn.

3. In a tension device for braider carriers, the combination with the body of a braider carrier having a hub and a bearing, a pawl with a trunnion seated in said bearing, a stud secured to the hub and a cop holder with teeth to coact with the pawl, the base of said cop holder acting as a retainer to hold the pawl trunnion in its bearing.

4. In a tension device for braider carriers, the combination with the body of the carrier, a cop holder having teeth and a pawl to coact with the teeth of the cop holder, of a yarn finger, a rocker on which the yarn finger is mounted, said rocker having an arm 26, a spring connected with said arm, and a swinging arm 32 to which the spring

is anchored, which arm can be secured in different positions by notches in the retainer 34 on the deck of the carrier.

5. In a tension device for braider carriers, the combination with the body of the carrier, a cop holder having a cupped base and teeth within the base, and a pawl extending within the base and engaging said teeth, of an arched standard having guide 10 pins, a rocker secured in position by the arch and having a crank within the arch, a yarn finger in said arch, sustained in vertical position by the guide pins and means to vary the intensity of resistance to movement 15 of the yarn finger.

6. In a tension device for braider carriers, the combination with the body of a carrier, having a hub and abutments 17, with bearings in said abutments, a rocker mounted in said bearings, and an arched standard 20 secured to the abutments by feet which hold the rocker in its bearings, of a stud secured to the hub of the carrier body, a cop holder mounted thereon having a cupped 5 base and teeth within the same, a pawl to engage the teeth and a yarn finger on the rocker and within the arched standard controlled in position by the tension of the yarn

to engage or disengage the pawl and cop holder.

7. In a tension device for braider carriers, the combination with the body of a carrier, a cop holder thereon having a cupped base, and a pawl which acts within said base to permit or prevent rotation of the cop 30 holder, of an arched standard having thread ways 35 to receive the yarn from the cop holder, a yarn finger within the standard to engage the yarn, and means co-operative with said finger whereby varying tension of the 40 yarn may cause the pawl to act.

8. In a cop-holder for braider carriers, the combination with a base, of a tubular stem, a bushing in said stem, and radially disposed blades let into both the bushing 45 and the stem with their edges projecting beyond the periphery of the stem and adapted to serve as spurs to rotatably secure the cop or bobbin on the stem.

In testimony whereof I affix my signature in presence of two witnesses.

SIMON W. WARDWELL.
